(57) **CLAIM**

The ornamental design for a light emitting device component, as shown and described.

DESCRIPTION

FIG. 1 is a perspective view of a light emitting device component showing the design;

FIG. 2 is a top view thereof;

FIG. 3 is a bottom view thereof;

FIG. 4 is a first side view thereof;

FIG. 5 is a second side view thereof, which is an opposing view of that shown in FIG. 4;

FIG. 6 is a third side view thereof; and,

FIG. 7 is a fourth side view thereof, which is an opposing view of that shown in FIG. 6.

The dashed broken lines are for illustrative purposes only. The dot-dashed broken lines represent boundaries of the claimed design. The broken lines form no part of the claimed design.
